UNITED STATES PATENT OFFICE.

PERRY E. TANNER, OF AKRON, OHIO.

FLUID-GAGE.

1,090,424.

Specification of Letters Patent. Patented Mar. 17, 1914.

Application filed August 5, 1912. Serial No. 713,423.

To all whom it may concern:

Be it known that I, PERRY E. TANNER,
a citizen of the United States, residing at
Akron, in the county of Summit and State
5 of Ohio, have invented new and useful Im-
provements in Fluid-Gages, of which the
following is a specification.

This invention relates to improvements in fluid gages used to determine the level of a fluid in a receptacle to thereby indicate the quantity contained therein.

The object of this invention is, primarily, to produce a gage of great simplicity, efficiency and cheapness in which the number of parts is reduced to a minimum without affecting in any way the accuracy of operation of the gage.

With the foregoing and other objects in view, the invention consists in the novel construction, combination and arrangement of parts constituting the invention to be hereinafter specifically described and illustrated in the accompanying drawings which form a part hereof wherein is shown the preferred embodiment of the invention, but it is to be understood that changes, variations and modifications can be resorted to which come within the scope of the claims hereunto appended.

30 In the drawings in which similar reference numerals indicate like parts in the different figures, Figure 1, is a vertical central sectional view of a gage embodying this invention positioned within a fluid receptacle; Fig. 2, is a plan view of the gage showing the graduated dial; and, Fig. 3, is an end view of the spiral element employed for carrying and rotating the indicating finger.

40 Referring to the drawings in detail the reference numeral 1 denotes a fluid receptacle with parts broken away as not being necessary for the proper understanding of the invention. The upper wall 2 of the receptacle is provided with an opening in which is positioned a cup-shaped member 3 constituting a closure member therefor and provided with a laterally-projecting flange 4 overlapping the upper wall 2 for holding the cup-shaped member in position. The face of upper surface of the cup-shaped member 3 is provided with indicia 5 constituting the graduated dial for indicating the contents of the receptacle. The

cup-shaped member is further provided with 55 a central opening 6 constituting a bearing for a purpose to be hereinafter described. Secured to the cup-shaped member 3 is a depending or vertically-arranged standard or post 7 projecting downwardly into the 60 receptacle, the lower end of which is laterally bent at right angles to constitute a step 8. The upper end of the post 7 is flattened on its inner side where it is secured to the cup-shaped member 3 and engages the side wall of the receptacle opening when the cup is in closing position therein. The step 8 may extend to and rest on the lower wall of the receptacle or may be spaced therefrom as desired. The step 8 70 is provided with an opening 9 constituting a bearing in which is mounted the lower end of a spiral member 10 preferably consisting of a wire bent in spiral convolutions and for instance, resembling a longitudinally-stretched coiled spring, the convolutions of which extend laterally a considerably greater distance than the diameter of the wire 10. The upper end of the member 10 is positioned in the opening 6 and bears at 75 its upper end an indicating finger 11 which is adapted to move in unison with the member 10 and to indicate on the graduated dial the volume of the contents of the receptacle. 80

In practice, I usually provide a pin 12 on 85 the face of the dial for arresting the rotation of the index finger 11 at the end of its rotary movement. In practice, I preferably provide the member 10 below the cup-shaped member 3 with a tight collar 12' and also 90 a collar 13 immediately above the step 8 to constitute stops for holding the member against lateral movement.

Vertically shiftably mounted on the standard 7 is a float 14 preferably embodying a hollow body through which extends a tubular member 15 to receive the standard 7. Extending laterally from the float 14 is an eye 16 which receives the member 10 and is slidably thereon. 100

It will be obvious that the float 14 may be constructed of some light substance such as cork or wood, or hollow and of metal, as shown, without departing from the scope of this invention.

In operation, when the level rises the float will move upwardly therewith and in doing so engages the various convolutions of the

member 10 sufficiently to rotate it and the index finger and indicates on the dial the volume of the contents of the receptacle.

I claim:

- 5 The combination with a fluid receptacle provided with an opening in its upper wall, of a removable cup-shaped member formed with a graduated dial positioned therein and constituting a closure member for said opening, said cup-shaped member further provided with a central perforation constituting a bearing, a depending L-shaped member with its upper end flattened on its inner side and engaging between the cup-shaped member
- 10 and the side of said opening and extending into said receptacle, a laterally projecting flange upon said cup-shaped member
- 15

overlying said flattened end, the horizontal portion of said L-shaped member provided with a bearing, a rotatable spiral mounted in said bearings, a hollow float, a central tube through said float mounted on the vertical portion of said L-shaped member, an eye upon said float receiving said spiral, and an index finger mounted upon the upper end of said spiral and movable across said dial.

In testimony whereof I have hereunto set my hand in presence of two subscribing witnesses.

PERRY E. TANNER.
